UNITED STATES PATENT OFFICE.

PAUL JOSEPH MOUSHEY AND JOHN ERLE WEST, OF YOUNGSTOWN, OHIO.

LOCKING LAMP-SOCKET.

1,201,075.

Specification of Letters Patent. Patented Oct. 10, 1916.

Application filed December 13, 1915. Serial No. 66,581.

To all whom it may concern:

Be it known that we, PAUL J. MOUSHEY and JOHN ERLE WEST, citizens of the United States, residing at Youngstown, in the county of Mahoning, State of Ohio, have invented a new and useful Locking Lamp-Socket, of which the following is a specification.

The present invention appertains to electric lamp sockets, and aims to provide a novel and improved socket of that character having unique means for locking the lamp to the socket, in order that the lamp cannot be removed by maliciously inclined persons, without breaking the same so that it will be useless, it being the object of the invention to provide a lamp socket from which the lamp cannot be stolen, although the lamp can be readily applied to the socket.

The invention resides in a novel assemblage of the component elements and includes a socket member mounted for rotation in one direction only, so that the lamp plug may be threaded within the socket member without difficulty and when the lamp is rotated in the opposite direction to unscrew the plug from the socket member, the socket member will rotate with the lamp. The device also includes locking means carried by the socket member, and a shell inclosing the locking means and socket member and held in place by the lamp, whereby said shell cannot be removed until the lamp is broken. To renew the lamp after it is burnt out, the lamp is broken and the shell removed, which enables the locking means to be manipulated for releasing the plug, the plug then being unscrewed and the parts assembled for the reception of a new lamp.

It is also within the scope of the invention to provide a locking lamp socket which is comparatively simple and inexpensive in construction and manufacture, which may be constructed in various styles for the reception of various lamps, and which will be thoroughly practical, reliable and efficient in use.

With the foregoing and other objects in view which will appear as the description proceeds, the invention resides in the combination and arrangement of parts and in the details of construction hereinafter described and claimed, it being understood that changes in the precise embodiment of

the invention herein disclosed can be made within the scope of what is claimed without departing from the spirit of the invention.

The invention is illustrated in the accompanying drawing, wherein:

Figure 1 is an elevation of the socket and lamp, with the shell illustrated in section. Fig. 2 is a sectional view on the line 2-2 of Fig. 1, portions being illustrated in elevation. Figs. 3 and 4 are enlarged cross sections taken on the lines 3-3 and 4-4, respectively, of Fig. 1.

In the drawing, the numeral 1 designates the socket member stamped from sheet metal or otherwise formed, and threaded as usual. The bottom of the socket member 1 is preferably swiveled to the insulating body 2 of the lamp socket, said socket member 1 and body 2 being inclosed by a sheet metal or other suitable shell 3 having the lamp end thereof contracted, as at 3a. Attached to the other end of the shell 3 is a cap 4 through which the conductors (not shown) are extended, the body 2 having a suitable switch for opening and closing the circuit.

As a convenient means of swiveling the socket member 1 to the body 2, a bolt or other pivot element 5 attached to the body 2 projects therefrom and has thereon an insulating bushing 6 engaged through the central portion of the bottom of the socket member 1, whereby the socket member can rotate about its axis. A spring contact 7 is attached to the bolt or pivot element 5 within the socket member 1 for the engagement of the central contact or terminal 8 of the plug 9 of the bulb or lamp 10. A contact 11 is carried by the body 2 and bears against the socket member 1, whereby the conductors can be connected with the bolt 5 and contact 11 to bring the lamp in the circuit, the bushing 6 insulating the socket member 1 from the bolt 5.

In order to prevent the rotation of the socket member 1 in one direction, said member is provided upon its periphery and adjacent its bottom with an annular series of ratchet teeth 12, and a spring pressed pawl or dog 13 is pivoted to the body 2 and cooperates with the ratchet teeth, for preventing the rotation of the member 1 in one direction. Thus, when the plug 9 is threaded into the socket member 1, the socket member is held in fixed position, whereas if an attempt is made to unscrew the lamp from the socket, the socket member 1 will merely

rotate with the plug 9 in order to avoid a wrenching strain upon the lamp as would be liable to break the same.

The locking means carried by the socket member 1 embodies a doubled or U-shaped guide 14 formed from a strip or other suitable material, and having its end portions bent angularly and soldered or otherwise secured to the periphery of the socket member 1, the socket member 1 being provided with a transverse slot 15 behind the guide 14 and in which a wedge-shaped locking member 16 works. Said member 16 fits slidably within the guide 14 and is held in place thereby, the inner edge of the member 16 having ratchet teeth 17 which project into the socket member 1 to contact with or engage the plug 9 of the lamp. The member 16 is pulled within the guide 14 by means of a wire or other suitable spring 18 having one end attached to the smaller end of the member 16, and having a coil 19 between its ends, the other end of said spring being soldered or otherwise secured, as at 20, to the socket member 1 adjacent the bottom thereof. The spring 18 has a tendency to pull the locking member 16 within the guide 14 to project the inner edge of the member 16 into the socket member 1. The member 16 is so arranged, that when the plug 9 is threaded into the socket member 1, the plug in engaging the member 16 will force the same to the left, as viewed in Fig. 3, whereby the plug can be threaded home without difficulty, but when there is an attempt made to unscrew the plug, the teeth 17 in engaging the plug, will cause the locking member 16 to be moved to the right, as viewed in Fig. 3, which will cause the locking member to wedge tightly between the guide 14 and plug. This will prevent the further unscrewing of the plug 9, and consequently, the lamp cannot be unscrewed without the member 16 being released. Furthermore, the socket member 1 will merely turn loosely when an attempt is made to unscrew the lamp from the socket. Since the socket member 1 and locking means are inclosed by the shell 3, the locking means cannot be released. The contracted end 3^a of the shell 3 bears against the bulb of the lamp, so that the lamp when in position holds the shell 3

in place, and the shell 3 cannot be removed until the bulb is broken. This can be readily done when the lamp is burnt out, whereby the shell 3 can be withdrawn from the body 2 to expose the locking member 16. Said locking member can then be pressed by the finger to release the plug, so that the plug can be unscrewed. Then, by reapplying the shell 3, a new lamp can be threaded into the plug and will be locked thereto.

The present invention is valuable for preventing the theft of the lamp from its socket, and can be altered in its details, within the scope of what is claimed without departing from the spirit of the invention.

The socket member 1 need not be mounted for rotation if this is not desired, since the socket member may be rigid as in ordinary lamp sockets. The pivotal mounting of the socket member, however, is of advantage when it is used for the reasons indicated.

Having thus described the invention, what is claimed as new is:

1. A lamp socket embodying a socket member having a guide, and a spring pressed wedge-shaped locking member slidably within said guide and arranged to wedge between the guide and plug of a lamp threaded within the socket by the unscrewing movement of the plug.

2. A lamp socket embodying a socket member having an outstanding U-shaped guide and a transverse slot, and a spring pressed wedge-shaped locking member slidably within said guide and slot and having a toothed edge projectable within the socket member to engage the plug of a lamp threaded within the socket member, whereby when an attempt is made to unscrew the plug from the socket member, the locking member is wedged between the plug and guide.

In testimony that we claim the foregoing as our own, we have hereto affixed our signatures in the presence of two witnesses,

PAUL JOSEPH MOUSHEY.
JOHN ERLE WEST.
